UNITED STATES PATENT OFFICE

ALBERT E. ROBINSON, OF CINCINNATI, AND WILLIAM L. SCHELLENBACH, OF WYOMING, OHIO, ASSIGNEES TO THE AMERICAN TOOL WORKS COMPANY, OF CINCINNATI, OHIO, A CORPORATION OF OHIO

DRILL ARM FOR METAL DRILLING MACHINERY

Application filed August 20, 1928. Serial No. 300,874.

In certain types of drilling machines there is usually an overhanging arm which, in radial drilling machines, is pivoted on a vertical axis to an upright post, or is rotatable with a column or sleeve about an upright post, so as to position the radial drill-arm in various radial positions for coactive relation with the work, which is usually supported on a work-table or base, or may be supported upon the floor adjacent to the machine.

The drill-arm carries a tool-slide on which there is a rotating spindle carrying the tool for co-operation with the work. The co-operation between the tool and the work causes upward stresses to be exerted upon the drill-arm, which upward stresses are great, especially in modern machine tool practice, in which high speed revolutions of the drilling tool and rapid feeding movements of the tool into the work are employed, for producing heavy cuts by the tool into the work, and the removal of thick chips from the work by the tool. Work of this character is also required to be extremely accurate, and any deviation of the tool from its intended path is extremely objectionable.

Drill-arms of this character have heretofore been usually made of cast iron, namely a gray cast iron, and the casting of drill-arms of this material is the present usual practice.

Efforts have been made to strengthen the drill-arm against flexure by casting the same in different cross-sectional forms, as by providing the same with ribs or flanges of various shapes and extending in various directions, or by providing cast drill-arms which are box-like or tubular in cross-section, all of which have failed in their purpose; especially as there is a limit to the amount of metal which a drill-arm may contain, due to its overhang and its weight, for producing a successful and marketable machine.

Means are usually provided in drilling machines of this character for raising and lowering the drill-arm with relation to the work-support for bringing the drill-arm as close to the work as is permissible in machine practice; the drill-arm being usually securely clamped to its pivotal support, post or column when in adjusted position. Such means are

usually manually operated or operated by power. When the parts are in adjusted or clamped relation, the work-support or base, the column, sleeve or post, and the drill-arm form a clamp arrangement, between the arms of which, represented by the work-support or base and the drill-arm, the work and the tool are located, the performance of the cutting operation causing raising stresses upon the arm for urging the arm away from the work-support or base, as in the direction of the arrow *a*.

Such raising stresses are in practice very great, and have heretofore resulted in flexing the drill-arm, regardless of its shape, to the extent at least of the natural flexure of the cast metal, and thereby reducing the capacity of the machine, for the reason that such flexing resulted in inaccurate work, for instance, in drilling a hole whose axis is out of line with the desired angle with relation to the plane of the work; in a hole whose axis was not straight, if different pressures were exerted in the course of the drilling; in a hole whose circumference was not a true cylinder, and in other objectionable features, and in undue strain upon the tool, the structure and the operating parts.

It is the object of our invention to avoid these objections, and we have accomplished this by providing the drill-arm with a tension-member to resist the yielding by the drill-arm to the cutting stresses.

It is the object of our invention further to provide the drill-arm with a tension member having greater resistances to yield for given area of cross-section than the resistance to yield of an equal area in cross-section of the drill-arm; further, to provide a cast drill-arm with a tension member resisting yield of the drill-arm, and anchored to the respective ends of the drill-arm; and, further, to arrange such tension member in oblique direction in the drill-arm and anchoring the same at obliquely opposite ends or corners of the drill-arm.

It is the object of our invention further to provide a cast metal drill-arm and a diagonal tension-member, and to exert compressive stresses upon the cast metal drill-arm,

and to anchor the respective ends of the tension-member to the cast metal drill-arm while the latter is in compressively stressed relation, for resisting yield in the drill-arm 5 to the work stresses; and, further, to form the cast metal drill-arm in the manner stated, and to then provide the same with the guide-ways for the tool-slide.

The invention will be further readily understood from the following description and claims, and from the drawings, in which latter:

Fig. 1 is a front elevation of an exemplifying drilling machine, partly broken away, 15 embodying our invention.

Fig. 2 is an end elevation of the same.

Fig. 3 is a side elevation of a rough casting for a drill-arm embodying a selected form of our invention.

Fig. 4 is a plan view of the same.

Fig. 5 is an angular section of the same, taken on the line 5—5 of Fig. 3.

Fig. 6 is a cross-section of the same, taken on the line 6—6 of Fig. 3.

Fig. 7 is a side elevation of the drill-arm in finished condition.

Fig. 8 is a cross-section of the same, taken on the line 8—8 of Fig. 7.

Fig. 9 is a side elevation of a core for the 30 casting of a drill-arm having the tension-bar imbedded therein.

Fig. 10 is a side elevation of a rough casting for a drill-arm showing a modification of our invention.

Fig. 12 is an angular section of the same, taken on the line 12—12 of Fig. 10.

Fig. 13 is a side elevation of the same in finished condition.

Fig. 14 is a side elevation of a further modification for the rough casting for the drill-arm; and,

Fig. 15 is a plan view of the same.

The exemplified drilling machine comprises a base 21 including a work-support 22. A stationary post 23 extends rigidly upwardly from the base, and has a rotatable sleeve or column 24, hereinafter referred to as a column, rotatable about the post on usual 50 bearings, and arranged to be clamped in adjusted positions to the post, by means of a usual split-bearing 25 at the bottom of the column and usual clamping means 26 therefor.

A drill-arm 28 extends above the work-support, and is exemplified as shiftable so as to place the drill-arm in desired position radially with relation to the post. The drill-arm is provided with a bearing 29 about the 60 column, this bearing being preferably a split-bearing, arranged to be clamped in adjusted elevational positions to the column by suitable clamping means, as at 30. The split bearing and clamping means may be of usual or ordinary construction.

A drill-arm of this character is usually adjustable up and down on the column, when the split-bearing 29 is in unclamped relation, by a usual upright screw 33 extending lengthwise of the column, and a usual nut 34 on the 70 drill-arm, of usual construction, one of these complementary members being arranged to be rotated for raising or lowering the drill-arm. When the drill-arm has been adjusted to desired radial position and to the desired elevational position, respectively, the clamping means 26 and 30 are clamped, for fixing the column rigidly to the post and fixing the drill-arm rigidly to the column.

The drill-arm is provided with guideways 36, 37, 38, 39, 40, extending lengthwise thereof, along which a tool-slide 41, provided with complementary guides, is arranged to slide or to be shifted lengthwise of the drill-arm by suitable manual or power means, for positioning a usual tool, for instance a drill 42, in a rotatable drill-spindle 43 on the tool-slide, at proper position with relation to the work, exemplified at 44, on the work-support. The tool-slide is arranged to be clamped in adjusted positions to the drill-arm, by usual means, and suitable and usual feeding means, operated either manually or by power, are arranged to feed the tool-spindle with relation to the work.

In modern machine tool practice the tool is required to operate rapidly on the work, and great strains are thereby exerted in a direction lengthwise of the tool-spindle away from the work, which must be resisted by the drill-arm, and great stresses are thus exerted upon the drill-arm. Any yielding in the drill-arm to such stresses results in inaccuracy in the work and in undue power requirements for rotating the tool.

It is the usual practice to make such drill-arm of a casting of metal, usually so-called gray cast iron, and attempts have been made to strengthen the drill-arm by casting the same in various shapes, as hereinbefore explained. We have found all such attempts to be inadequate for obtaining the highest efficiency and output in a machine of this character, and have conceived the idea of absorbing the natural resiliency in the cast metal of the arm, or of amplifying and supplementing the resistance of the cast metal of the arm, by the resistance of a tension member so placed as to resist the bending raising stresses upon the arm throughout the various positions of the drill-slide lengthwise of the arm, and we have preferred to arrange said tension member slanting with relation to the guideways on the drill-arm, and have found such arrangement most advantageous for the further reason that a drill-arm is usually a long overhanging structure limited in height and cross-section owing to weight of the metal.

We prefer to provide a tension-member

which is of steel, and has great tensile strength, and great resistance to load stresses by the tool. It may be instanced, as an example, but not as a limitation, that the ultimate load resistance of cast iron in a drill-arm as usually constructed, is twenty-two thousand pounds ultimate per square inch, and that its safe working load is six thousand pounds per square inch. A steel tension member such as we employ has preferably a safe load resistance of ninety thousand pounds or more per square inch of cross-section.

A cast metal drill-arm of the character mentioned as usually heretofore employed has an initial yield or spring in the metal tending toward inaccuracy in operation.

It is the object of our invention to absorb such initial resilience or spring, which we accomplish by exerting forces upon the cast metal drill-arm in directions preferably counter to the directions of forces upon the drill-arm in the operation of the tool upon the work, and setting or anchoring the drill-arm in such assumed condition.

Referring now to Figs. 3 to 6 inclusive, the cast metal drill-arm is exemplified at 51. Its interior is provided with a core-hollow 52, ribs 53 extending inwardly from the outer walls of the drill-arm, openings 54 being in the ribs. A tension-member 55 is anchored at 56 at one of its ends, at one end 57 of the drill-arm, being preferably anchored at one corner 58 of the drill-arm.

This anchoring is formed by imbedding the tension-member in the core 59 for forming the cavities in the drill-arm, one end of said tension-member, provided with annular grooves 60, projecting out of said core, and being imbedded in the cast metal of the drill-arm when the drill-arm is cast. The tension-member is diagonally arranged in said core for producing the result instanced.

The tension member is provided with a reduced end 61, the outer end of which is screw-threaded, as shown at 62. A bushing 63, provided with an annular flange 64 at its outer end, is received about this reduced end and in the bore 65 left by the core. A nut 66 is threaded over the outer threaded end of the tension-member, and is resisted by the end face 67 of said bushing, which end face is in a plane preferably perpendicular to the axis of the tension-member. The bushing 63 may be on the core. The flange 64 is resisted by the casting.

The casting may be provided with guideway formation 36', 37', 38', 39' and 40', which, when finished, become the guideways 36, 37, 38, 39 and 40.

The casting may also be formed with a formation 29' which, when finished and provided with suitable slits and clamping means, becomes the clamp bearing 29 for the arm 65 about the column.

Strains are now applied to the cast metal drill-arm for absorbing the initial yield or spring in the same, to produce a dead resisting mass for resisting the strains of the tool. This may be accomplished by bending or compressive stresses applied to the drill-arm, or by drawing upon the nut 66, for exerting tension stresses upon the tension-bar 55 and compressive stresses upon the cast metal drill-arm, for absorbing such initial upward yield or spring of the cast metal drill-arm. These stresses may be applied to flex the outer end of the arm downwardly with relation to its inner end.

It may be desirable for operative or constructive reasons in finishing or use of the drill-arm, that the parts extending from the cast metal end of the drill-arm shall be removed, in which case we prefer to provide substitute anchoring means for the outer end of the tension member, for instance, in the form of pins 68, received through mating holes in the cast metal drill-arm and complementary hole sectors in the extension 61 and the bushing 63, for securely anchoring the tension-member and the outer end of the cast metal drill-arm together.

The anchoring means between the outer end of the tension-member and the outer end 69 of the drill-arm, are preferably located in the corner 70 of the drill-arm, diagonally or obliquely opposite to the corner 58 of the drill-arm at which the opposite or inner end of the tension-member is anchored.

After such substitute anchoring of the outer end of the tension-member, the nut 66 may be removed, and the outer ends of the tension-member and of the bushing projecting beyond the outer end of the cast metal drill-arm may be removed in suitable manner, as by planing, shaping or milling, and the remaining surface finished to present a straight and unbroken end surface for the drill-arm.

It may be stated as an exemplification, but not as a limitation, that the cross-sectional area of the tension-member may be three and three-quarter inches, and in the proportion shown in the drawings with relation to the cross-sectional area of the casting, and that the tension-member may be a steel bar, for instance of alloy steel having very high tensile strength, for instance, an alloy steel containing chemical cleansing ingredient, such as manganese, nickel or vanadium, to produce a steel having a very dense fibre. The tensile strength of such steel is as high as one hundred and seventy-five thousand pounds per square inch of cross-section of the bar. The bar is preferably a flat bar with its width dimension extending in upright direction. The bolts and nuts for the bars are preferably of the same material as the material of the bar.

In Figs. 10, 11, 12, and 13, we have exem-

plified a modification, in which parts similar to parts shown in Figs. 3 to 6 inclusive are identified by similar reference numerals raised to the series 100. In this exemplification, the tension-member is anchored to the lower part of the inner end 157 of the overhanging portion of the drill-arm by means of pins 175 received through registering holes in the casting and in one end of the tension-member, the other end of the tension-member being provided with a threaded socket 176, in which the threaded end of a bolt 177 is received, the inner end of the head 178 of the bolt bearing against the inclined face 167 of a lug 164 on the outer end of the drill-arm. The bolt is arranged to rotate in a slanting hole 165 in the outer end of the drill-arm.

When the proper bending and compressive action upon the cast metal drill-arm and the proper tensile force upon the tension-bar has been provided, the outer end of the tension-bar and the outer end of the drill-arm are preferably connected by anchor-pins 168 received through registering holes in the drill-arm and the tension-bar. Upon such assemblage of the parts, the head 178 and the outer end of the bolt 177 and the lug 164 may be removed, and the outer end face of the drill-arm provided with a suitable finish to cover the shank of the bolt.

Referring to Figs. 14 and 15 inclusive, which show a further modification, parts similar to the parts shown in Figs. 3 to 6 inclusive are identified by similar reference numerals raised to the series 200. In this modification the respective ends of the tension-member 255 are threaded as at 280, 281. The tension-member 255 is shown round and is preferably of the same cross-sectional area as the tension-members 55, 155. The respective ends of the tension-member 255 are respectively received through bores 282, 283, in lugs 284, 285, in the diagonally opposite corners 258, 270, in the drill-arm. Nuts 286, 287, are threaded about the respective ends of the rods, being received against slanting end faces 288, 289, of the lugs 284, 285, respectively at the lower inner end and at the upper outer end of the cast metal drill-arm. These end faces are perpendicular to the axis of the rod.

When the proper compressive action has been had upon the cast metal drill-arm and proper tension applied to the tension-bar, as by applying bending and compressive forces to the cast drill-arm, and by rotating the nuts, the tension-member is preferably anchored at its respective ends, as by anchoring pins 292 at the lower inner corner 258 and by anchoring pins 293 at the upper outer corner 270 of the drill-arm, the pins being received through registering holes in the cast metal drill-arm and the tension-bar.

If desired, the supplementing anchoring pins may be omitted, and the nuts 286, 287,

which may remain complete and in place, be relied on as the anchoring means, for the reason that the positions of the nuts and the lugs therefor will in the positions shown be unobjectionable.

After the cast metal drill-arm has been thus operated on, and deflected, and the shape of the drill-arm thus fixed, the drill-arm is provided with the guideways, as 36, 37, 38, 39, 40, along which the tool-slide is arranged to be moved for adjusting the tool to proper position with relation to the work. Distortion of the guideways, which would otherwise result from treating the cast metal drill-arm in manner stated, is avoided, and guideways, which are parallel with each other and with the proper plane of movement of the point of the tool in the drill-spindle, and which are in straight lines, are thus assured in the finished drill-arm and during operation.

The bearings for shafts, rods and other parts extending longitudinally of the drill-arm are also preferably formed after the drill-arm has been treated in accordance with our invention, so that the same may be parallel and in line throughout the length of the drill-arm, and remain so during operation.

The groove 95 for the toothed rack 96, is also cut and the rack inserted in the groove, after the drill-arm has been deflected to absorb the natural flexure of the casting of the drill-arm and fixed in its deflected form in accordance with the teachings of our invention, and other parts may be applied to the drill-arm after such flexure and fixing. The rack mentioned is the usual rack employed for lateral positioning movements of the drill-head on the drill-arm.

We have explained our invention, and have presented several examples of its embodiment. It will be readily understood that other embodiments of the same may be employed and that changes may be made without departing from the spirit of our invention as contained in the accompanying claims.

Having thus fully described our invention, what we claim as new, and desire to secure by Letters Patent, is:

1. A radial drill-arm for a radial metal drilling machine, said drill-arm comprising a cast body of metal having an upright bearing portion arranged to be received about the upright column of the drilling machine and a laterally extending overhanging arm-portion, a tension member extending obliquely in said arm-portion of said cast body throughout the greater portion of the length of said arm-portion, and means whereby said tension member is anchored obliquely in a single direction at its respective ends to said cast body, and said cast body between said anchoring means being under compression.

- and said tension member being under tension to resist deflection in said drill-arm.
2. A radial drill-arm for a metal radial drilling machine having an upright post and 5 an upright column thereabout, said drill-arm adapted to be adjusted up and down on said upright column and to be radially positioned about said upright post, said drill-arm comprising a cast body of metal having an upright bearing portion about said column and a laterally extending arm-portion, a tension member extending obliquely in said arm-portion of said cast body throughout the greater portion of the length of said 10 arm-portion, and means whereby said tension member is anchored under tension at its respective ends to obliquely opposite end portions of said cast body, with said cast body under compression between said obliquely opposite ends, said arm-portion of said drill-arm under such compression provided with longitudinal guideways for a drill-slide, and said tension member extending obliquely in a vertical plane crosswise of said guideways. 15
- 25 3. A radial drill-arm for a metal radial drilling machine having an upright column, said radial drill arm comprising a cast body of metal having a vertical bearing portion and a laterally extending arm-portion, said bearing portion arranged to be received about said upright column and adapted to be adjusted up and down on said column, said arm-portion provided with a bore extending lengthwise of said arm-portion, a tension member in said bore extending obliquely throughout the greater portion of the length of said arm-portion, and means whereby said tension member is anchored at its respective ends to obliquely opposite corners of said 20 arm-portion of said cast body, said drill-arm provided with longitudinal guideways for a drill-slide, said tension member extending in a vertical plane obliquely across the horizontal planes in which said longitudinal 25 guideways are located, and said tension member acting to resist deflection in said drill-arm by upward working stresses upon said drill-arm.
4. A radial drill-arm for a radial drilling machine having an upright column, said drill-arm comprising a cast body of metal having an upright bearing and an overhanging arm-portion extending laterally from said upright bearing, said upright bearing arranged to be received about said upright column and to be adjusted up and down on said column for adjusting said drill-arm to elevation, said overhanging portion provided with straight laterally extending parallel 35 guideways for a drill-head and a tension member in said overhanging arm-portion extending obliquely crosswise of said guideways and having one end thereof fixed to said casting adjacent said bearing at one corner of 40 said overhanging arm-portion and its other end fixed to said casting adjacent a diagonally opposite corner of the outer end of said overhanging arm-portion and resisting bending stresses on said overhanging arm-portion of said casting, for maintaining said guideways straight and parallel. 70
- 45 5. A radial drill-arm for a radial drilling machine having an upright column, said radial drill-arm comprising a cast body of metal having an upright bearing and an overhanging arm-portion, said upright bearing adapted to be received about said upright column and to be adjusted up and down thereon, said overhanging arm-portion provided with longitudinal straight and parallel guideways for a drill-slide provided with complementary parallel guideways, and a tension member in said overhanging arm-portion having substantially greater tensile strength than the tensile strength of said cast overhanging arm-portion and extending in said cast body obliquely to said longitudinal parallel guideways, the respective ends of said tension member fixed under tension to obliquely opposite end portions of said overhanging arm-portion for maintaining said longitudinal guideways straight and parallel. 80
- 55 6. In a radial drilling machine comprising an upright post and an upright column rotatable thereabout, a drill-arm comprising a cast body of metal having an upright bearing and an overhanging arm-portion extending laterally from said bearing, said upright bearing adapted to be received about said column and arranged to be adjusted up and down on said column, said arm-portion provided with straight longitudinal parallel guideways adapted to coordinate with complementary guideways on a drill-slide adapted to be adjusted along said overhanging arm-portion, a tension member having substantially greater tensile strength than the tensile strength of said cast body, said tension member extending obliquely in said overhanging arm-portion of said cast body, and anchoring means between the respective ends of said tension member and diagonally opposite corners of said overhanging arm-portion, said tension member being under abnormal tension and said casting under abnormal compression, the lines of force of said tension and compression being substantially parallel and counter to each other, and said tension member extending obliquely crosswise of said guideways for maintaining said guideways straight and parallel with each other. 95
- 65 7. A radial drill-arm for a radial drilling machine comprising a cast body of metal having an upright bearing and an overhanging arm-portion extending laterally from said upright bearing, said drill-arm adapted to be adjusted up and down on the upright column of the drilling machine, said overhanging arm-portion provided with straight 100
